Application January 27, 1937, Serial No. 67,306

Term of patent 14 years

To all whom it may concern:

Be it known that I, Fred C. Taylor, a citizen of the United States, residing at Hammondsport, county of Steuben, State of New York, have invented a new, original, and ornamental Design for a Display Stand for Bottles or the like, of which the following is a specification, reference being had to the accompanying drawing, forming a part thereof.

Figure 1 is a perspective view of the display stand showing my new design; and

Figure 2 is a top plan view thereof.

The dominant feature of the invention is the

pyramid-shaped display stand having cut-out portions along its edges to support the bottles being displayed, each in a rearwardly inclined position. The edges of the cut-out portions closely follow the contour of the exterior surface of the bottles displayed, which may be of any desired shape.

I claim:

The ornamental design for a display stand for bottles or the like, substantially as shown and described.

FRED C. TAYLOR.
